UNITED STATES PATENT OFFICE.

EDWIN DONALDSON, OF BROOKLYN, NEW YORK.

LABELING MACHINE.

1,419,546.

Specification of Letters Patent. Patented June 13, 1922.

Application filed February 27, 1920. Serial No. 361,867.

To all whom it may concern:

Be it known that I, EDWIN DONALDSON, a citizen of the United States, and a resident of Brooklyn, Kings County, and State of New York, have invented certain new and useful Improvements in Labeling Machines, of which the following is a specification, reference being had to the accompanying drawings, forming a part thereof.

10 This invention relates to apparatus for applying labels or wrappers to articles such as cans or other containers.

The general objects of the invention are to provide an automatic machine which will require practically no other attention than the supplying of labels and articles to be labeled and which will operate to rapidly, accurately and securely apply the labels or wrappers to the cans or other articles.

20 A special object of the invention is to insure the proper fastening of the label with but a relatively small amount of glue or other adhesive. In this connection, it is one of the aims of the invention to improve the adhesive applying mechanism so as to prevent "gumming" the machine and to enable the removal of practically the entire adhesive applying mechanism from the machine as a unit.

30 Other objects and features of the invention relate to the mechanism for wrapping the labels about the articles, the means for transferring the labels from the hopper to the wrapping devices and to special mechanism for stopping the operation of the machine in case the articles being labeled should become exhausted.

All of the foregoing and other features of the invention will appear as the specification 40 proceeds.

In the accompanying drawings I have disclosed the invention as embodied in a machine for labeling relatively small cylindrical cans or containers, but would have it understood that this is only one of the uses 45 of the invention and that changes and modifications may be made without departure from the true scope and spirit of the invention.

50 In the drawings referred to Figure 1 is a side elevation and part sectional view of the complete machine.

Figure 2 is an end view of the same.

55 Figure 3 is an enlarged sectional view of the gate mechanism and article feeding

plunger, as taken on substantially the plane of line 3—3 of Figure 1.

Figure 4 is a view of these parts as taken looking in the direction of the arrow 4 in Figure 3.

60 Figure 5 is a broken and partly sectional view of the transfer mechanism, this view being taken on substantially the plane of line 5—5 of Figure 2.

Figure 6 is a vertical sectional view of the transfer arm operating mechanism taken on substantially the plane of line 6—6 of Figure 5.

Figure 7 is a broken detail view of the rack and gear mechanism for operating one 70 of the label applying rolls.

Figure 8 is a plan view of the detachable glue-pot unit.

Figure 9 is a view of the doctor rolls, with the vibrating arms which carry the same 75 shown as broken away.

Figure 10 is a plan view of one of the labels to show the manner in which the adhesive is applied in relatively narrow transverse strips to the end and intermediate portions thereof.

Figures 11, 12, 13 and 14 illustrate successive steps in the application of the label to the can.

Figure 15 is a sectional and more or less 85 diagrammatic representation of the adhesive applying mechanism.

Figure 16 is a detail view of one of the adhesive applying arms.

Figure 17 is a perspective view of one of 90 the completely labeled cans.

Figure 18 is a general view of the stop mechanism as taken on substantially the plane of lines 18—18 of Figures 1 and 19.

Figure 19 is a sectional view of the same 95 taken on substantially the plane of line 19—19 of Figure 18.

Figures 20 to 32 are diagrammatic views illustrating successive steps in the operation of the machine.

Figure 33 is a detail view illustrative of the follower or yieldable hold-down for the labels.

Figure 34 is a detail view illustrative of the trip mechanism for the first label applying roll.

Figure 35 is a view of the operating mechanism for the second label applying roll.

To facilitate an understanding of the in- 110

vention, I will first briefly describe the operation of the machine shown and for that purpose will refer to the diagrammatic views, Figures 20 to 32 respectively.

5 In Figures 20, 21 and 22 I have illustrated how first the glue or other adhesive is applied to the labels. In these views 40 designates a stack of labels supported in a suitable hopper with the bottom label exposed. 10 41 designates a glue-pot in which operate glue rolls 42, 43 and 44 spaced to be engaged by the doctor or transfer rolls 45, 46 and 47 and which latter rolls are carried by swinging arms 48 operating about the center 49. 15 50 and 51 designate adhesive applying and label transferring arms swinging about the center 56 and designed to contact the lower-most label at points adjacent the ends thereof. 53 designates an adhesive applying arm operating about the center 54 and positioned to engage the intermediate portion of the label at a point between the two transfer arms 50, 51.

20 The transfer rolls 45, 46, and 47 are positioned to register with the glue rolls 42, 43 and 44 respectively and rolls 45 and 47 are positioned to register with transfer arms 50 and 51 while the intermediate roll 46 is positioned to register with the single adhesive applying arm 53.

25 In Figure 20 the doctor rolls are indicated as having engaged the glue rolls and the single adhesive applying arm 53 is indicated as on its upward stroke and as about to engage 30 the upwardly swinging doctor roll 46. In Figure 21 the adhesive applying arm 53 has engaged and applied a transverse strip of adhesive to the bottom label and the doctor rolls 45 and 47 are engaging the arms 50, 51 of the transfer device.

35 In Figure 22 the arm 53 has left the label, the spring hold-back fingers 55 carried thereby preventing the label from following said arm, the transfer arms 50, 51 are swinging 40 towards the stack of labels and the doctor rolls are swinging down to again engage the glue rolls.

45 In Figure 23 the transfer arms are shown 50 engaged with the bottom label to apply transverse strips of adhesive to the end portions of the label. This view also shows how the transfer arms are carried by a shaft 56 having a half-round portion 57 on the end thereof rotating in a part-round pocket or 55 depression 58 at the end of a track 59, and a flat side 63. This view also shows how the transfer arms are operated by a sliding rack 60 engaging a gear 61 on the shaft 56.

60 As the swinging arm 62 which operates 65 the rack moves to the right, the transfer shaft 56 is rotated, causing the transfer arms to swing away from the stack of labels and, by reason of the adhesive, to carry the bottom label with them. The transfer shaft 65 continues to rotate until a position is reached

such as indicated in Figure 24 where the half-round portion 57 of the shaft rotates out of the pocket 58 and the flat side 63 of such half-round portion registers with track 59, whereupon the shaft is free to slide over 70 said track. This released condition is indicated in Figure 24, which also shows the label 64 adhering to the transfer arms.

75 As the lever 62 swings further to the right, the rack, carrying with it the transfer shaft, is shifted to the position indicated in Figure 25 where the label is then supported in position to be operated on by the wrapping devices.

80 Figure 26 is a view of the label as supported in this last position, this view being taken looking in the direction of the arrow 26 in Figure 25. In this view two of the articles which are being labeled are indicated at 65 in the lower end of the feed chute 66, 85 the lower article being held by a gate 67 which is connected with a second or cut-off gate 68 by a walking beam 69.

90 This walking beam is oscillated as indicated in Figure 27 to lift the hold-back gate 67 and at the same time to drop down the cut-off gate 68 to stop the second article. The released article falls down onto the label which is then supported above two spaced 95 label applying members or rolls 70, 71.

95 Figure 28 shows how the released article is then forced down against the label between the two label applying rolls by means of the two plungers 72, 73, which hold the article, with the label wrapped thereabout 100 against the support 74 while rolls fasten down the ends of the label.

105 In Figure 29, the first label applying roll 70 is indicated as having been rocked about the right-hand side of the supported article to wrap the first end portion of the label about the article.

110 Figure 30 illustrates how at the end of this label applying movement, the roll 70 is tripped from contact with the label so that 115 on its return stroke it will not contact with the label.

115 After the first label applying roll has done its work, as shown in Figure 31, the second roll 71 is advanced about the supported article to wrap the label thereabout and to seal the other end of the label down over the first secured end.

120 While the second label applying roll is in its upper position, as shown in Figure 32, the supporting head 74 on which the article has rested during these last mentioned movements, is retracted and is tilted by reason of its engagement with a stop 75 so as to discharge the wrapped article onto a discharge 125 chute 76 which delivers the same onto a carrying-off belt or conveyor 77.

130 From this it will be seen that relatively narrow transverse strips of adhesive are first applied to the intermediate and end portions

of the label and that the label is applied to the article by first engaging the intermediate strip of adhesive therewith, then bringing first one end of the label into adhering engagement with the article and then fastening the other end of the label down over the first secured end thereof.

Taking up now the detailed construction of the machine illustrated, it will be seen in Figures 1 and 5 that the label hopper is made up of a series of fingers 80 disposed to form an open-ended box or compartment for holding a stack of labels and having inturned lower ends at 81 to support the stack and to releasably hold the bottom label.

As the labels are removed from the bottom, the stack is forced downward by a follower 82, which rests on the top of the stack and which holds the stack down against the upward thrust of the adhesive applying arms by spring plate 83 carried by the post 84 of the follower and having a sliding, frictional, gripping engagement over the relatively stationary post 85. The engagement of this spring hold-down over the post 85 is such as to permit the plate to readily slide downwardly over the post, but to cause it to bind against the post when an upward thrust is exerted on the follower. The follower thus drops down with the stack and at each new adjustment yieldingly opposes the upward thrust of the adhesive applying levers against the bottom of the stack.

The glue-pot 41, as shown particularly in Figures 8 and 15 is in the form of a pan having ribs or flanges 86 slidably fitting in guide-ways provided therefor in the supporting frame 87 (Fig. 1) and the shaft 88 which carries the glue rolls 42, 43 and 44 is journaled directly therein so that said rolls are removable as a unit with the glue-pot. This glue roll shaft carries a gear 89, which when the pot is inserted in the machine, meshes with a drive gear indicated at 90 in Figure 1. Said shaft also carries a gear 91 for meshing with a gear 92 on the shaft 93 which carries the doctor rolls 45, 46 and 47.

A special feature in the construction of the glue-pot is that it is recessed or provided with bays 94 and 95 in one side thereof to receive the gears 89 and 91, the shaft 88 extending through the walls of these bays and the glue rolls operating in the portions of the pot or tank at the sides of such bays. Suitable scrapers are indicated at 96 for cleaning the glue rolls and removing the excess glue.

The doctor roll shaft 93 is journaled in the swinging arms 48 which are loosely engaged on the shaft 49 and are yieldingly actuated by said shaft through the medium of the spring arms 97 engaged by a pin 98 carried by an arm 99 fast on the shaft, said spring arms 97 engaging a pin 100 on one

of the arms 48. (Figs. 1 and 15.) With this construction, it will be seen, that the arms carrying the doctor rolls will be oscillated with the shaft 49 but may yield in either direction, for instance, on the down stroke when the doctor rolls engage with the glue rolls and also while the doctor rolls are in engagement with the adhesive applying arms.

The doctor rolls are positively rotated when in contact with the glue rolls by the engagement of the gear 91 on the glue roll shaft with the gear 92 on the doctor roll shaft (Figs. 8 and 9) and similarly the doctor rolls 45 and 47 are positively rotated when in engagement with the glue-carrying pads or surfaces 101 of the transfer arms by the engagement of the gears 102 on the doctor roll shaft with racks 103 carried by the transfer arms at the side of the glue surfaces 101. This latter feature will possibly be best understood by reference to Figure 15 in which position of the parts the transfer arms 50, 51 are swinging toward the label stack 40 and the doctor rolls are swinging downward in front of the transfer arms.

The hold-off fingers for preventing the labels from adhering to the intermediate adhesive applying arm 53 are illustrated in detail in Figures 15 and 16, in which latter view it will be seen that these fingers form the bifurcated lower end or forks of a spring plate secured to the arm 53, said fingers standing at opposite sides of the adhesive carrying portion or pad 104 of the arm so as to straddle the doctor roll 46 and standing above the plane of the adhesive portion 104 so as to yield on contact with the bottom label and, on the retraction of the arm, to expand and hold back the label so as to prevent it following the adhesive carrying portion of the arm.

The label, with the three strips of adhesive applied thereto, is illustrated in detail in Figure 10, where 105 designates the narrow transverse strip of adhesive applied to the central or intermediate portion of the label and 106 and 107 designate the relatively narrow transverse strips applied by the rolls 45 and 47 to the opposite end portions of the label.

The operating mechanism for the transfer arms is disclosed in detail in Figures 5 and 6 where the rack 60 is shown as sliding in a guide-way 108 formed in the side of the framing 109, said rack having at 110 a sliding, rotating motion connection with the lower end of the operating lever 62 which is pivoted in the frame at 111. The track 59 for the flat side 63 at the end of the transfer shaft 56 is disposed at the outer side of the framing 109 and the framing is constructed with a slot 112 for the passage of the end portion of the shaft. The racks may be slidingly confined in their guide-ways 108

by overstanding flanges 240 on the adjacent sides of the transfer arms 50 and 51, and the shaft is shown as rotatably supported in the flanged boxes 112^a sliding in the guiding 5 slots 112.

At the end of the track 59 where the depression 58 is provided for the turning of the shaft, a stop 113 is provided to act as a buffer for the sliding shaft bearing and to 10 positively limit the extent of sliding movement of the shaft.

Additional means for holding the shaft against rotation in the course of its sliding movement is provided in the machine illustrated in the form of a stationary rib or ledge 114 projecting inward from the side of the framing and arranged to be engaged by a roll 115 carried by an arm 116 upstanding from the side of the transfer arm.

20 This construction, it will be seen, assists the half-round section of the shaft in holding the shaft against turning movement and this track 114 terminates at a point to permit the shaft to rotate as soon as it reaches 25 the pocket 58 at the end of the track 59. The track 114 also is of value in that it serves to support the weight of the transfer arms during the sliding movement, and overcomes any binding tendency of the half-round locking portion in sliding over the track 59.

The swinging lever 62 which operates the transfer arms is shown as actuated by a rocker arm 117 outstanding from the pivotal center of said lever and connected by a link 118 with a lever 119 pivoted at 120 and carrying a roll 121 (Figure 1) in engagement with a cam groove in a suitable cam 122 on shaft 123. The adhesive applying 40 arm 53 is shown as operated in similar fashion by means of a rocker arm 124 connected by a link 125 with a lever 126 pivoted on shaft 127 and having a roll 126^a engaging a cam on shaft 123. Cam lever 128 45 (Fig. 1) carries a roll 129 in engagement with a cam groove in cam 130 which also is mounted on the cam shaft 123. This cam lever 128 is shown connected at its upper end by means of a link 131 with a rocker arm 50 132 which is fixed on the doctor roll shaft 49, the cams and the lever and link connections described being so proportioned as to 55 effect the proper relative movements of the parts described.

55 The transfer arms are shown as cushioned at the end of their forward advancing movement (Figures 1 and 5) by means of a buffer 133 similar to the buffer 113 provided at the end of the track 59. These buffers insure 60 quiet action in bringing the parts to rest at the proper point.

The wrapping devices are illustrated in detail in Figures 3, 4, 7, 34 and 35. As shown in these views, roll 70 is journaled on 65 a lever or between a pair of levers 134 piv-

oted at 135 on a swinging arm 136 carried by a shaft 137. This shaft is journaled substantially concentrically at one end of the supported can and carries a gear segment 138 engaged by a rack 139. This rack slides 70 in an inclined guide-way 140 and is actuated by a link 141 which is connected with a cam lever 142 pivoted at 143 and carrying a cam roll 142^a in engagement with the cam 144 (Fig. 1).

The label applying roll 70 is yieldingly pressed against the label on the supported article by a spring or springs 145 coiled about the pivotal axis 135 and bearing on the roll carrying arms 134.

Roll 70 is tripped substantially at the end of its advancing or forward movement about the can by means, consisting in the illustration, of the trip or stop 146 disposed in the path of the rear end of the pivoted roll carrying arm and arranged in the forward swinging movement of said lever to engage a cam surface 147 on the upper edge thereof to rock the lever in such a way as to lift the forward end and the roll carried thereby out of contact with the end of the label which has just been applied to the can. The roll is held in this tripped position by a stop member 148 pivoted on an extension 136^a of the arm 136 at 149 and rocked by a spring 150 to carry the rear or inner end thereof 151 into engagement with a stop shoulder 152 on the roll carrying lever. This tripped condition of the roll is illustrated in Figure 34 and the roll is held thus tripped during the entire retractive or return movement thereof. At the end of the return movement the pivoted stop 148 is tripped to again restore the roll to its article-engaging position, the means for such purpose comprising a trip 153 disposed in the path of the outer end of the pivoted stop 148 and arranged to be engaged thereby at the end of the retractive movement to rock the trip, as indicated in Figure 34 to free the inner end thereof from the shoulder 152. This tripping of the label applying roll prevents the end of the label which has just been applied to the article from being lifted away from the article in the return stroke of the 115 roll and also obviates any tendency there might be for the roll to wrinkle the label on its return stroke.

The second label applying roll 71 is carried by a spring-pressed lever 154 (Fig. 3) 120 pivoted at 155 on a vibrating arm 156 which latter is carried by a shaft 157 disposed substantially concentrically at the opposite end of the supported can from the other roll carrying arm 136. This shaft 157 is provided with a gear segment 158 engaged by a rack 159 similar to the other rack but working in a guide-way 160 disposed on an incline which is the reverse of the incline of the first rack. This rack like the first rack 130

is operated by a link 161 connected with a swinging lever 162 carrying a cam roll 163 (Fig. 2) in engagement with a cam 164.

The cams last referred to and the connections therefrom are so designed as to effect the sequence of action previously described, that is to cause the first roll to advance and wrap one end of the label about the can and to then trip and retract, the other roll then advancing to wrap the other end of the label about the can and secure the same over the first secured end of the label.

The plungers 72, 73 which force the article and hold it down against the label between the label applying rolls and onto the support 74 (Figures 3 and 4), are carried by a slide 165 working in a guide-way 166, said slide carrying an outstanding pin or stud 167 engaged by the forked end of a lever 168 on rock shaft 169, which carries a rock arm 170^a (Figure 1) operated by a link 170 which is connected at its lower end with a lever 171 pivoted at 172 and carrying a cam roll 173 engaged with a cam 174 on the cam shaft 123. The plungers 72, 73 are shown in Figure 4 as set in the opposite edge portions of slide 165 by having head portions 175 at their upper ends engaged in corresponding seats in the face of the slide and one of these plungers, namely 73, is shown as having a pivotal movement about its center of support at 175 and as being yieldingly pressed toward the adjacent end of the can or other article by a spring 176. This permits the plunger mechanism to accommodate itself to slight variations which may occur in the size of the cans and also causes the plunger to fit snugly over a bead 177 which may ordinarily be provided on the end of the can. Also, this plunger 73 is shown as undercut as indicated at 178 to receive this bead. Both the plungers 72 and 73 are shown as recessed so as to fit over the corners or end edges of the article so as to exert a centering effect on the article as well as to engage over the top of the same for the purpose of exerting the downward thrust thereon.

A lost motion connection is provided in the present illustration for effecting the proper sequence of action between the gate mechanism and the plunger mechanism, said connection being shown as a pair of spaced stops 179, 180 on the back of the slide 165 (Figure 3) and arranged in the retraction of the slide to engage an extension 181 on the forward end of the walking beam 69. This walking beam is shown as coupled to the two gates 67, 68 by means of the slots 182, 183 provided at opposite sides of the pivotal center 184 thereof and receiving the pins 185 and 186 on the gates 67 and 68 respectively.

In the position illustrated in Figure 3

where the plungers have descended and forced the can and with it the label between the two spaced label applying rollers, the upper stop 180 has engaged the forward end of the walking beam and rocked the same downwardly so as to lower the gate 67 and raise the gate 68. The lower gate is then in holding engagement with the last article in the chute. On the upward movement of the slide 165 and approximately at a time when the plungers have cleared the passage for the articles, the stop 179 engages the end 181 of the walking beam and rocks the same upwardly so as to lift the lower gate 67 to thereby release the last article, and lower the upper gate so as to catch the next to the last article. This upper or cut-off gate 68 is preferably provided with a buffer to cushion the impact of the row of articles in the chute, said buffer being shown as a plate 187 yieldingly supported on the upper face of the cut-off gate by a spring 188. The two gates 67 and 68 are shown as guided respectively in suitable slots or guide-ways 189, 190 provided in the upper frame work of the machine.

After the label or wrapper has been completely applied to the article and firmly secured thereto, the article is discharged from the wrapping mechanism, in the machine illustrated, by tilting the article support 74 in the manner indicated in Figure 32. Referring to Figure 3 it will be seen that the article support 74 is in the nature of a head pivoted at 191 to one side of the center of a spring supported post 192, said pivoted head having a bearing on the relatively fixed stop or shoulder 75 and being held normally engaged with said shoulder by the spring 193. It will be clear from the views referred to that when the post or plunger 192 is in its upper position, the pivoted head 74 will form a firm support for the article and that when the post 192 is retracted or depressed the pivoted head will slide over the stop 75 as a fulcrum and will be tilted in such a way as to discharge the wrapped article therefrom and toward the left in Figure 3. The post 192 is operated to thus discharge the article by means of a suitable cam 194 engaged by the cam roll 195 (Figure 1) and the parts are preferably so timed that this discharging movement will take place at the time that the second label applying roll 71 is in upraised condition, as illustrated in Figure 32 and therefore out of the way of the discharging movement of the article.

The wrapped or labeled articles may be carried off and away from the machine by means of a suitable belt conveyor such as illustrated at 77 in Figures 2 and 32, said conveyor receiving the articles from the discharge chute 76 which, at its lower end, is provided with a suitable guide 196 for drop-

ping the articles into position on the conveyor.

In addition to the features above disclosed, my invention involves also the provision of suitable stop mechanism for interrupting the operation of the machine when there are no articles present to be labeled. This mechanism is illustrated particularly in Figures 1, 2, 18 and 19 and comprises, generally speaking, a clutch on the drive shaft 197 and which is controlled by the presence or absence of articles in the feed chute 66. The drive shaft 197 is shown as having a bevel gear connection 198 at its inner end with the cam shaft 123 and as provided at its outer end with a drive pulley 199. This drive pulley is coupled to the shaft by means of a pin 200 arranged to take into a slot or slots 201 in the face of the pulley and sliding in a groove 202 in a collar 203 which is fast on the shaft. This clutch pin is normally forced outward to engage in the pulley slot by a spring 204 and the operation of this pin is controlled by a plunger 205 having a shoe 206 at its lower end received in an annular groove 207 in the collar 203, said shoe having a portion of reduced width at its forward edge at 208 to act as a wedge for the purpose of engaging in a transverse or inclined slot 209 in the outer face of the clutch pin. The clutch controlling plunger 205, when the machine is in operation, is held supported in an elevated position where the shoe at the lower end thereof is clear of the clutch pin, the means illustrated for this purpose comprising a latch 210 arranged to engage a pin 211 on the plunger, said latch being pivoted at 212 and normally held engaged with said pin by a spring 213.

Provision is made in the machine illustrated for manually tripping the latch, the same comprising a handle 214 pivoted on the frame of the machine at 215 and carrying a pin 216 working in an inclined cam slot 217 in the upper end of a trip lever 218 which is pivoted at 219 and engages at its lower end with the upper extended end 220 of the latch member.

It will be seen from Figures 18 and 19 that when the handle 214 is depressed, the pin 216 will, through the cam connection illustrated, rock trip lever 218 and cause said lever to rock the upper end of the latch lever 210 in such a way as to free the hook on the lower end thereof from engagement with the pin on the clutch plunger. The plunger when thus released is thrown downward by its own weight and also by the action of a spring 221 in the illustration, causing the shoe on the lower end thereto to drop in the annular groove in the collar, in which position the reduced forward end of the shoe enters the slot in the face of the clutch pin and withdraws the same free of the seat

in the driving pulley. This stops the machine practically instantaneously and prevents the adhesive supplying parts from gumming up any of the other parts of the machine.

The machine may again be started after articles have been supplied to the feed chute by simply lifting up the control lever 214 which causes the pin 216, operating in a slot 222 in the upper end of the plunger to pick up the plunger and lift it to a position where the latch 210 will again snap into holding engagement with the pin 211.

Provision is made for automatically stopping the machine, in the case illustrated, by a feeler or detector disposed in the path of the articles being fed to the wrapping mechanism and shown as a spring arm 223 supported on an insulating block 224 and having an active portion disposed in the feed chute and of a length sufficient to be contacted by the last two articles in the chute, said spring arm having an introverted portion 225 overstanding a contact member 226 on the insulating support 224. The relatively insulated contacts 225 and 226 are connected in circuit by means of wires 227, 228 with a control magnet 229 shown in the form of a solenoid having a core 230 connected with a pivoted lever 231 which in turn is connected with a link 232 connected with the sustaining latch 210. Interposed in the circuit connections for this magnet is a suitable battery or other source of electric current and there will ordinarily be included in this circuit a suitable control switch 233 and preferably a suitable annunciator in the nature of a buzzer or the like, as shown at 234, to give notice to an operator, who may thus be enabled to take care of several machines.

With the construction just described, the contacts will remain out of engagement so long as there are articles in the feed chute but as soon as the last article is dropped down to the wrapping mechanism, the contact spring, being no longer restrained, will engage the relatively stationary contact 226, and establish a circuit through the trip magnet which, operating through the connections described, will trip the latch and release the clutch plunger which will operate in the same way as before described to stop the machine. In stopping the machine the parts will ordinarily come to rest on the completion of the application of the label to the last article in the machine and before the adhesive applying arms have operated to take another charge of adhesive. In this way gumming of the machine is avoided and at the same time the operation on the last article in the machine is completed.

The machine operates rapidly and effectively to firmly secure the labels or wrappers. By suitably modifying the parts, ar-

ticles of different sizes and shapes may be operated upon and these and other changes are contemplated as coming within the scope of my invention. I also wish it understood that the terms and illustrations employed herein are used in an illustrative rather than in a limiting sense, except, however, for such limitations as may be required by the prior art.

10 The construction illustrated particularly in Fig. 3 enables the article supporting head to yield under the downward pressure of the article feeding plunger, the extent of such yielding movement being governed by the pin 192^a operating in the slot formed in the upper end of the rod member 192.

The magazine for the labels is preferably made in two independently adjustable sections to enable the labels being positioned, 20 so that they will properly register with the articles to which they are applied. For this purpose, I have shown in Figs. 1 and 5, the fingers 80 as arranged in two sets each of which set is carried by an angular bracket 25 80^a which is adjustably secured to the adjacent side frame by the bolt and slot connections indicated at 80^b. With this construction it is possible to adjust one side or the other of the hopper so as to square up the 30 stack of labels and thereby cause them to feed accurately.

The glue-pot may be detachably secured in the machine as by means of a latch construction such as that indicated at 250 in 35 Fig. 15. In this figure I have also indicated a stop 251 engaged by the glue pot when properly seated in the machine. The latch is indicated as spring operated and as adapted to snap into engagement with a shoulder 40 252 on the glue-pot. The stop 251 limits the inward movement of the glue-pot and the spring latch serves to hold the glue-pot in engagement with such stop. Hence the glue-pot is accurately positioned in the machine and the gearing carried thereby is held 45 in proper engagement with the drive gearing. This construction also insures that the adhesive applying rolls will properly cooperate with the rolls in the glue-pot.

50 What I claim is:

1. In a labeling machine, a label support, an adhesive applying arm swinging toward and away from said support at one side thereof and a second adhesive applying arm 55 swinging toward and away from the support at the opposite side thereof.

2. In a labeling machine, a label support, a pair of transfer arms for engaging the labels on said support, means for applying adhesive to said transfer arms, an independent adhesive applying arm operating on the labels at a point between the transfer arms and means for first swinging the adhesive applying arm into engagement with the la-

65 bels and for thereafter swinging the transfer arms into engagement with the label.

3. In a labeling machine, the combination with a label support, of an adhesive applying device comprising a pivoted arm with the free end thereof forming an adhesive 70 carrying surface for engagement with the labels on the support, and a bifurcated leaf spring stripper affixed to said arm and straddling said adhesive carrying surface and standing above the plane thereof. 75

4. In a labeling machine, the combination with the label support and an adhesive applying arm for engagement with the labels in said support, drive gearing and a relatively removable glue-pot provided with a 80 glue roll and with a gear for operating the same and arranged for engagement with the drive gearing aforesaid.

5. In a labeling machine, a supporting frame, a glue-pot removably mounted in 85 said frame, a shaft journaled in said glue-pot, a glue roll on said shaft, a gear on the shaft, gearing on the supporting frame arranged to be engaged by said gear when the glue-pot is mounted in said frame, a doctor 90 roll for engagement with said glue roll and gearing between the doctor roll and the glue roll shaft for positively driving the doctor roll when the same is engaged with the glue roll. 95

6. In a labeling machine, a glue-pot, a positively driven glue roll operating therein, a glue applying arm, a doctor roll operating between the glue roll and said arm and engaging gearing carried by the doctor roll 100 and arm respectively.

7. In a labeling machine, a glue-pot, a positively driven glue roll operating therein, a glue applying arm, a doctor roll operating between the glue roll and said arm, and engaging gearing between the glue roll and doctor roll and between the doctor roll and arm respectively. 105

8. In a labeling machine, a label support, a glue applying arm swinging toward and 110 away from said label support, a glue-pot, a glue roll operating in said pot, a swinging doctor roll operating between the glue roll and the glue applying arm and engaging gearing carried by the doctor roll and arm 115 and by the doctor roll and glue roll respectively.

9. In a labeling machine, a label support, a glue applying arm swinging toward and away from said label support, a glue-pot, a glue roll operating in said pot, a swinging doctor roll operating between the glue roll and the glue applying arm and engaging gearing carried by the doctor roll and arm 120 and by the doctor roll and glue roll respectively, comprising a gear carried by the doctor roll, a rack on the glue applying arm for engaging said gear and a gear car- 125

ried by the glue roll for engaging the gear of the doctor roll.

10. In a labeling machine, glue applying arms swinging in opposite directions and a 5 yieldingly supporting glue supplying arm operating between said glue applying arms.

11. In a labeling machine, a label hopper, a glue applying arm operating at one side of said hopper, glue applying arms operating 10 at the opposite side of the hopper and offset laterally with respect to the first arm, a glue-pot provided with glue rolls in line with the respective arms and a doctor provided with rolls in line with the several 15 arms.

12. In a labeling machine, a label hopper, a glue applying arm operating at one side of said hopper, glue applying arms operating at the opposite side of the hopper and offset laterally with respect to the first arm, a glue-pot provided with glue rolls in line 20 with the respective arms, a doctor provided with rolls in line with the several arms and means for operating said parts to bring the 25 doctor rolls alternately into engagement with the different arms.

13. In a labeling machine, a label hopper, a glue applying arm operating at one side of said hopper, glue applying arms operating 30 at the opposite side of the hopper and offset laterally with respect to the first arm, a glue-pot provided with glue rolls in line with the respective arms, a doctor provided with rolls in line with the several arms and means for operating said parts to first effect 35 engagement of the single arm with its doctor roll and thereafter to effect engagement of the other arms with the doctor rolls provided therefor.

40 14. In a labeling machine, a glue roll, a swinging glue applying arm, a swinging doctor roll operating between the glue roll and the arm and means for holding the doctor roll yieldingly engaged with both the 45 glue roll and the arm.

15. In combination, label transferring arms, a shaft supporting said arms provided with a plane face, a track engaged by said 50 plane face to hold the shaft against rotation and provided with a recess to admit rotary movement of the shaft and means for sliding the shaft on the trackway and for rotating the same in the plane of said recessed portion.

55 16. In combination, a track having a partially circular depression, a shaft arranged to turn in said depression and having a part-round portion for sliding on the track, transfer arms carried by the shaft and 60 means for sliding the shaft over said track and for rotating the same in the depression aforesaid.

17. In combination, a track having a partially circular depression, a shaft arranged

to turn in said depression and having a part-round portion for sliding on the track, transfer arms carried by the shaft, means for sliding the shaft over said track and for rotating the same in the depression aforesaid and means for guiding the transfer arms and 70 for preventing rotary action during the sliding movement thereof.

18. In combination, a sliding rack, a slidingly supported shaft having a gear engaged by said rack, means for reciprocating the 75 rack and means for holding the shaft against rotary movement during a portion of the stroke of the rack and for holding the shaft against sliding movement during another portion of the stroke of the rack and label 80 supporting means carried by said shaft.

19. In combination, a sliding rack, a slidingly supported shaft having a gear engaged by said rack, means for reciprocating the 85 rack, means for holding the shaft against rotary movement during a portion of the stroke of the rack and for holding the shaft against sliding movement during another portion of the stroke of the rack and label 90 supporting arms carried by said shaft.

20. In combination, a sliding rack, a slidingly supported shaft provided with a gear engaging said rack, said shaft having a substantially half-round portion and a track engaged by the flat side of said half-round 95 portion and provided with a part-round portion to receive the substantially semi-cylindrical part of the half-round portion and label supporting means carried by said shaft.

21. In combination, a sliding rack, a slidingly supported shaft provided with a gear engaging said rack, said shaft having a substantially half-round portion, a track engaged by the flat side of said half-round 100 portion and provided with a part-round portion to receive the substantially semi-cylindrical part of the half-round portion and label supporting arms carried by the shaft.

22. In combination, a sliding rack, a slidingly supported shaft provided with a gear 110 engaging said rack, said shaft having a substantially half-round portion, a track engaged by the flat side of said half-round portion and provided with a part-round portion to receive the substantially semi-cylindrical 115 part of the half-round portion, label supporting arms carried by the shaft, a guide track and a member carried by one of the label supporting arms and engaging said guide track.

23. In combination, a sliding rack, a shaft supported to slide and provided with a gear in mesh with the rack, an arm carried by the shaft, a track and a member carried by said arm and engaging the track and a label 125 carrier mounted on said shaft.

24. In combination, a reciprocating slide provided with gear teeth, a label transfer

arm having gear teeth in mesh with the gear teeth of said slide, a guide carried by said arm and a track engaged by said guide.

25. In combination, a sliding rack, a swinging and slidably supported transfer arm provided with gear teeth in mesh with said rack, a track, a rotation-preventing member carried by the arm and engaging said track and a stop for limiting the sliding 10 movement of the arm, said track being relieved adjacent said stop to free the rotation-preventing member and permit swinging movement of the transfer arm.

26. In a machine of the character described, an article chute constructed to support a series of articles, label applying mechanism at the base of said chute, a gate for holding the last article of the series, a cut-off gate for restraining the articles in 20 rear of said last article and a yielding buffer carried by said cut-off gate.

27. In a machine of the character described, an article chute, label applying mechanism at the base of said chute including a reciprocating plunger, a rocking lever, a lost motion connection between the plunger and lever and article control gates connected with said lever and operating in the chute.

28. In a labeling machine, an article chute, 30 spaced members at the base of said chute, means for supporting a label over said members, a pusher for forcing an article down against the label and between the spaced members and gate mechanism in the chute 35 for holding articles in said chute and means for automatically operating said gate mechanism for releasing an article in advance of the downstroke of the pusher.

29. In a labeling machine, an article chute, 40 a gate operating to hold the last article in the chute, means for supporting a label at the base of the chute, spaced members below the thus supported label, means for operating the gate to release the last article and a pusher for forcing the released article downward against the supported label and between the spaced members.

30. In a labeling machine, an article chute, a gate operating to hold the last article in 50 the chute, means for supporting a label at the base of the chute, spaced members below the thus supported label, means for operating the gate to release the last article, a pusher for forcing the released article 55 downward against the supported label and between the spaced members and means for relatively rotating the spaced members about the article.

31. In a labeling machine, an article chute, 60 a gate for holding back the last article in the chute, labeling devices at the base of the chute and a plunger for engaging the article released by the gate, said plunger having a connection with the gate for op-

erating the same on the upstroke of the 65 plunger.

32. In a labeling machine, an article chute, a gate for holding back the last article in the chute, labeling devices at the base of the chute and a plunger for engaging the article 70 released by the gate, means for lifting the plunger clear of articles in the chute and a lost motion connection between the plunger and gate for operating the gate when the plunger is retracted clear of the article 75 passage.

33. In a machine of the character described, an article chute, a plunger operating in the lower end of said chute, a gate disposed in the chute in advance of the plunger, 80 means for retracting the plunger with respect to the chute and a lost motion connection between the plunger and gate for operating the gate on the retractive movement of the plunger. 85

34. In a machine of the character described, an article chute, a plunger operating in the lower end of said chute, a gate disposed in the chute in advance of the plunger, means for retracting the plunger 90 with respect to the chute, a lost motion connection between the plunger and gate for operating the gate on the retractive movement of the plunger and lost motion connections between the plunger and the gate for operating the gate substantially at the end of the retractive and projecting movements of the plunger. 95

35. In a machine of the character described, an article chute, a plunger operating in the lower end of said chute, a gate disposed in the chute in advance of the plunger, means for retracting the plunger 100 with respect to the chute, a lost motion connection between the plunger and gate for operating the gate on the retractive movement of the plunger, and a second reversely operating gate connected with the first gate. 105

36. In a machine of the character described, an article chute, label applying 110 mechanism at the base of said chute, a pair of gates operating in said chute, a walking beam connected with said gates, a plunger and spaced stops carried by said plunger and positioned to engage said walking beam. 115

37. In a machine of the character described, spaced members, an article support at one side of said spaced members, label supporting means at the opposite side of said spaced members, and a pusher operating at said opposite side of the spaced members for forcing an article against the supported label between said members and into supported engagement with the support. 120

38. In a machine of the character described, spaced members, an article support at one side of said spaced members, a pusher operating at the opposite side of the spaced 125

- members for forcing an article between said members and into supported engagement with the support and means for rocking the support to discharge the article therefrom.
- 5 39. In a machine of the character described, spaced members, an article support at one side of said spaced members, a pusher operating at the opposite side of the spaced members for forcing an article between said members and into supported engagement with the support, means for shifting one of the members about the article on the support and means for rocking the support to discharge the article therefrom.
- 10 40. In a machine of the character described, an article chute, label applying devices at the end of said chute including an article support, a discharge chute at one side of said support and means for rocking the support to discharge an article thereon toward said discharge chute.
- 15 41. In a machine of the character described, a post having a pivoted head forming an article support, means for seating an article on said support and means for rocking the pivoted head to discharge the article therefrom.
- 20 42. In a machine of the character described, a post having a pivoted head forming an article support, means for seating an article on said support, means for rocking the pivoted head to discharge the article therefrom comprising a stop engaged by the pivoted head and means for shifting the post to cause the head to fulcrum on said stop.
- 25 43. In a machine of the character described, a post, a head pivoted on said post and forming an article support, an abutment forming a stop limiting the pivotal movement of said head, a spring for rocking the head toward said stop, means for shifting the post to cause the head to rock against said stop and means for seating an article on the head.
- 30 44. In a labeling machine, an article support, label applying means for engaging opposite sides of an article on said support, means for shifting the label applying means away from one side of the supported article and means for rocking the support to discharge the article toward said side.
- 35 45. In a labeling machine, label applying devices and means for holding an article in position to be operated on by said devices comprising plungers engaging over the edges at the opposite ends of the article.
- 40 46. In a labeling machine, label applying devices and means for holding an article in position to be operated on by said devices comprising plungers engaging over the edges at the opposite ends of the article, one of said plungers having a groove in the operative face thereof to receive a rib on the end of the article.
47. In a labeling machine, means for supporting an article, a label applying device, means for oscillating said label applying device in a substantially circular path and substantially concentrically about the supported article and means for tripping the label applying device from engagement with the article at the end of its concentric movement in one direction and for restoring said device into position for engagement with a supported article substantially at the end of its concentric movement in the opposite direction.
- 50 48. In a labeling machine, means for supporting an article, a label applying device, means for advancing said device in a substantially circular path and substantially concentrically about the article and for then withdrawing the same and means for tripping said device away from the supported article substantially at the end of its concentric advancing movement and for again restoring said device in position for engagement with a supported article substantially at the end of its withdrawing concentric movement.
- 55 49. In a label applying machine, means for supporting an article, a label applying roll, means for advancing said roll in a substantially circular path part-way about the supported article and for then tripping the same from engagement with the article, a second label applying roll and means for advancing said second label applying roll in a reverse direction in a substantially circular path part-way about the supported article.
- 60 50. In a label applying machine, means for supporting an article, a label applying roll, means for advancing said roll in a substantially circular path part-way about the supported article and for then tripping the same from engagement with the article, a second label applying roll, means for advancing said second label applying roll in a reverse direction in a substantially circular path part-way about the supported article.
- 65 51. In a labeling machine, an article support, oscillating arms swinging about the supported article, spring-pressed label applying rolls carried by said arms and means for removing one of the rolls in the course of its movement about the supported article from the contact with said article.
- 70 52. In a labeling machine, means for supporting an article, a swinging arm provided with a gear segment, a reciprocating rack engaged with said segment, a spring pressed lever pivoted on said swinging arm, and a

- label applying roll carried by the said spring pressed pivoted lever.
53. In a labeling machine, means for supporting an article, swinging arms arranged at the opposite sides of the supported article, gear segments connected with said arms, reciprocating racks engaging with said segments and label applying rolls carried by the arms.
54. In a labeling machine, means for supporting an article, swinging arms arranged at the opposite sides of the supported article, gear segments connected with said arms, reciprocating racks engaging with said segments, label applying rolls carried by the arms and means for sequentially operating the racks in reverse directions.
55. In a labeling machine, an article support, swinging arms at the opposite sides of said support, gear teeth carried by said arms, oppositely inclined racks engaged with said gear teeth, means for operating said racks and label applying members carried by the arms.
56. In a labeling machine, a swinging arm, a lever pivoted on said swinging arm, a label applying device mounted on said lever, a pivoted stop on the swinging arm, a shoulder on the lever and cooperating with the pivoted stop to hold the lever shifted in one position and a trip disposed in the path of the swinging movement of the pivoted stop to free the same from engagement with the shoulder on the lever.
57. In a labeling machine, a swinging arm, a lever pivoted on said swinging arm, a label applying device mounted on said lever, a pivoted stop on the swinging arm, a shoulder on the lever and cooperating with the pivoted stop to hold the lever shifted in one position, a trip disposed in the path of the swinging movement of the pivoted stop to free the same from engagement with the shoulder on the lever and a stop disposed in the path of swinging movement of the lever to rock the same to bring the shoulder thereon into position for holding engagement by the pivoted stop.
58. In a labeling machine, a swinging lever, a lever pivoted on said swinging lever, a label applying member carried by the pivoted lever, a shoulder on one of said levers and a pivoted stop on the other lever for engagement with the shoulder to hold the levers in a predetermined relation.
59. In a labeling machine, a swinging lever, a lever pivoted on said swinging lever, a label applying member carried by the pivoted lever, a shoulder on one of said levers, a pivoted stop on the other lever for engagement with the shoulder to hold the levers in a predetermined relation and means for tripping said stop in the course of the swinging movements of the levers.
60. In a labeling machine, a swinging lever, a lever pivotally mounted on said swinging lever, a label applying member mounted on said pivoted lever, means for rocking the pivoted lever in the course of the swinging movement of the first lever and a pivoted stop mounted on one of the levers for holding the pivoted lever in its relatively rocked position.
61. In a labeling machine, a swinging lever, a lever pivotally mounted on said swinging lever, a label applying member mounted on said pivoted lever, means for rocking the pivoted lever in the course of the swinging movement of the first lever, a pivoted stop mounted on one of the levers for holding the pivoted lever in its relatively rocked position and means for rocking said pivoted stop to release it from its holding position.
62. In a labeling machine, a swinging lever, a lever pivoted on said swinging lever, a label applying member carried by said pivoted lever, a shoulder on one of the levers, a pivoted stop on the other lever for engagement with said shoulder, a spring for shifting said stop into holding engagement with the shoulder and a trip for shifting the stop in the opposite direction.
63. In a labeling machine, a swinging lever, a lever pivoted on said swinging lever, a label applying member carried by said pivoted lever, a shoulder on one of the levers, a pivoted stop on the other lever for engagement with said shoulder, a spring for shifting said stop into holding engagement with the shoulder, a trip for shifting the stop in the opposite direction and a trip positioned to be engaged by the pivoted lever to cause re-engagement of the pivoted stop and shoulder.
64. In a labeling machine, a swinging lever, a lever pivoted thereon, a label applying roll carried by said pivoted lever, a trip positioned to rock the pivoted lever in the course of the swinging movement in one direction, means for holding said lever in its rocked condition during the movement in the reverse direction and means for tripping said holding means substantially at the end of such reverse movement.
65. In a labeling machine, an article support, a swinging arm, a label applying member pivotally mounted on said swinging arm, means for holding said label applying member engaged with the supported article in the movement of the swinging arm in one direction, means for tripping said member out of engagement with the supported article at the end of such movement and for holding the same tripped during the return movement of the swinging arm, means for tripping the member substantially at the end of the return movement into position.

for engagement with a supported article, a second swinging arm, a label applying member carried thereby and means for operating said swinging arm to carry the second label applying member about the supported article at the completion of operation of the first label applying member.

66. In a machine of the character described, a plunger, a head pivoted thereon and forming an article support, label applying devices for operating on an article on said support, a discharge conveyor at one side of the plunger and means for operating the plunger to rock the support to discharge 15 the labeled article upon the discharge conveyor.

67. In a machine of the character described, stop mechanism including a clutch, a shiftable member for controlling said 20 clutch, an electro-magnet controlling said member, a supply passage for the articles being wrapped and contact mechanism disposed in said passage and controlling the electro-magnet.

68. In a labeling machine, stop mechanism, comprising a clutch, a plunger controlling said clutch, a spring for shifting said plunger in one direction, a latch for holding said plunger against the tension of 30 said spring, a manually operative trip for said latch and an automatic trip for said latch controlled by the presence or absence in the machine of the articles to be wrapped.

69. In a labeling machine, stop mechanism comprising a clutch, a plunger controlling said clutch, a spring for shifting said plunger in one direction, a latch for holding said plunger against the tension of said spring, a hand lever connected with the plunger, a 40 rocking lever operated by said hand lever and engaged with the latch and an automatic trip controlled by the presence or absence in the machine of the articles to be wrapped for releasing the latch independently of the hand lever.

70. In a labeling machine, stop mechanism comprising a clutch, a plunger controlling said clutch, a spring for shifting said plunger in one direction, a latch for holding 50 said plunger against the tension of said spring, a hand lever connected with the plunger, a rocking lever operated by said hand lever and engaged with the latch, an automatic trip for releasing the latch independently of the hand lever and comprising an electromagnet having an armature connected with the latch and a circuit controller for said electro-magnet disposed in the path of movement of the articles being 55 labeled in the machine.

71. In a machine of the character described, a feed chute, gate mechanism controlling delivery of articles through said chute, a detector in the chute adjacent said 65 gate mechanism, labeling devices arranged

to operate on articles released by the gate mechanism and stop mechanism controlled by the detector.

72. In a machine of the character described, a shaft having a collar with an annular groove therein and provided with a channel at substantially right angles to said groove, a bolt slidably mounted in said groove and provided with a cam face, a shoe fitting in the groove and arranged to engage the cam face to displace the bolt, a driving member on the shaft having a seat to receive said bolt, article wrapping means driven by the shaft and means controlled by the articles for automatically controlling the bolt.

73. In a machine of the character described, a shaft having an annular groove and a slot disposed at substantially right angles thereto, a bolt slidably mounted in said groove and provided with a cam slot in the outer face thereof, a shoe slidably fitting in the annular groove, a driving member on the shaft provided with a seat to receive the bolt and means for projecting and retracting the shoe to engage and disengage the same with respect to the cam slot in the bolt, article wrapping means driven by the shaft and means controlled by the articles for automatically controlling the bolt.

74. In a machine of the character described, a shaft having an annular groove and a slot disposed at substantially right angles thereto, a bolt slidably mounted in said groove and provided with a cam slot in the outer face thereof, a shoe slidably fitting in the annular groove, a driving member on the shaft provided with a seat to receive the bolt and means for projecting and retracting the shoe to engage and disengage the same with respect to the cam slot in the bolt, said shoe being of substantially the full width of the annular slot but having a portion of reduced thickness at one end thereof to form an entering wedge for engagement in the cam slot, article wrapping means driven by the shaft and means controlled by the articles for automatically controlling the bolt.

75. In a machine of the character described, a reciprocating slide, article-engaging fingers projecting from said slide, one of said fingers having a pivotal connection with the slide and a spring for yieldingly forcing said finger toward the other finger, means for reciprocating said slide to engage the fingers with the opposite ends of an article and label affixing means for applying a label to an article engaged by the fingers.

76. In a machine of the character described, a frame having a guide-way, a rack sliding in said guide-way, a shaft, a label carrier on said shaft, a gear on said shaft meshing with the rack, said shaft being bodily 125 slideable with the rack and an annular flange 130

on said shaft overlying the rack to slidingly confine the same in the guide-way.

77. In a machine of the character described, a glue-pot provided with bays in one side thereof, a shaft journaled in said glue-pot and extending across said bays, rolls on the shaft operating within the glue-pot and gears on the shaft received in said bays outside the glue-pot, label applying mechanism and gearing from said label applying mechanism in mesh with the gears on said shaft.

78. In a machine of the character described, a glue-pot having a bay in one side thereof, a shaft journaled in the glue-pot and extending across said bay, glue rolls on said shaft operating in the glue-pot at opposite sides of the bay and a gear on that portion of the shaft which crosses the bay, label applying mechanism and gearing from said label applying mechanism to the gear on the shaft.

79. In a machine of the character described, a supporting frame, a drive gear supported by the frame, said frame being provided with a guideway and with a stop, a glue pot slidable in said guideway into engagement with said stop, a latch for releasably securing the glue pot thus engaged with the stop, gearing carried by the glue pot for actuating adhesive applying mechanism, said gearing being arranged to be held in meshing engagement with the drive gear on the frame when the glue pot is thus engaged.

80. In a labeling machine, spaced label applying members, means for positioning an adhesive label at one side of said members, means for forcing an article against the thus supported label and between the members aforesaid, a support adapted to receive and support the article thus forced between said members, and means for rotating first one label applying member in one direction, tripping said member out of engagement with the article, and then rotating the other label applying member in the opposite direction about the article thus engaged on said support.

81. In a labeling machine, spaced label applying members, means for positioning an adhesive label at one side of said members, means for forcing an article against the thus supported label and between the members aforesaid, a support adapted to receive and support the article thus forced between said members, means for then rotating first one label applying member and then the other label applying member about the article thus engaged on said support, and means for

withdrawing the support from supporting engagement with the article to free the same from the label applying members.

60

82. In a labeling machine, means for supporting a stack of labels, an adhesive applying arm swinging toward the bottom of the stack from one side thereof, a second adhesive applying arm swinging toward the bottom of the stack from the opposite side thereof, and means for sequentially operating said arms.

83. In a labeling machine, a label transferring arm, a shaft supporting said arm and provided with a plane face, a track engaged by said plane face to hold the shaft against rotation and provided with a depression to permit rotary movement of the shaft, and means for sliding the shaft on the track and for rotating the same as it reaches said depression.

84. In a labeling machine, a label transferring arm, a shaft supporting said arm and provided with a plane face, a track engaged by said plane face to hold the shaft against rotation and provided with a depression to permit rotary movement of the shaft, and means for sliding the shaft on the track and for rotating the same as it reaches said depression, said means including a slide provided with a rack, a gear element on the shaft engaging said rack, and an arm for reciprocating the slide.

85. In a labeling machine, an article chute, label applying mechanism at the base of said chute, spaced article control gates operating in said chute, a walking beam pivoted intermediate its ends at a point between the gates and connected adjacent its opposite ends with said gates, and means for operating said walking beam.

86. In a labeling machine, an article chute, label applying mechanism at the base of said chute, spaced article control gates operating in said chute, a walking beam pivoted intermediate its ends at a point between the gates and connected adjacent its opposite ends with said gates, and means for operating said walking beam, said means including a plunger for engaging the articles in the chute and a lost motion connection between the plunger and walking beam for positively operating the walking beam in opposite directions.

110

In witness whereof, I have hereunto set my hand, this 20th day of February, 1920.

EDWIN DONALDSON.
